UNITED STATES PATENT OFFICE.

CHARLES J. STABERG, OF BROOKLYN, NEW YORK.

MUZZLE ATTACHMENT FOR SCATTERING SHOT.

SPECIFICATION forming part of Letters Patent No. 579,502, dated March 23, 1897.

Application filed March 19, 1896. Serial No. 583,969. (No model.)

To all whom it may concern:

Be it known that I, CHARLES J. STABERG, a citizen of the United States, and a resident of Brooklyn, in the county of Kings and State 5 of New York, have invented certain new and useful Improvements in Firearms, of which the following is a specification, reference being had to the accompanying drawings, forming a part thereof, in which similar letters of 10 reference indicate corresponding parts.

This invention relates to firearms, and the object thereof is to provide a gun or firearm which is adapted to scatter the shot or projectiles as they leave the muzzle thereof; and with 15 this object in view the invention consists in the construction, combination, and arrangements of parts hereinafter described and claimed.

The invention is fully disclosed in the following specification, of which the accompanying 20 drawings form a part, in which—

Figure 1 is a top plan view of the end of the barrel of a gun provided with my improvement; Fig. 2, a longitudinal transverse section thereof; Fig. 3, a vertical transverse section thereof. Figs. 4 and 5 are plan views of 25 details of the scattering device.

In the drawings forming part of this specification, A represents the end of the barrel of a gun; and mounted thereon is a tubular 30 sleeve B, which is provided at one side with an oblong casing b, which is open at its outer end, and mounted within the oblong casing b is a plate C, the inner surface of which conforms to the surface of the barrel and the 35 outer surface of which is convex in cross-section, and mounted in said casing and resting against or in contact with the plate C is a a plate-spring D, the inner end of which is bent outwardly, so as to increase the power of the 40 spring, as shown at d, and the outer end of which is provided with a loop d², formed by bending the end of the plate.

Mounted within the oblong casing b is a curved spring G, one end of which projects 45 through the side thereof, as shown at g, and the other end of which is bent to correspond with the frame of the casing B in cross-section and rests in a transverse notch or recess formed in the top thereof, and the inner end 50 of the spring D is provided at one side with notches or recesses d³ and d⁴, the last of which is formed close to the end thereof and is pro-

vided with an abrupt shoulder, while the sides of the notch or recess d³ are both inclined; and by means of this construction the spring 55 D may be withdrawn until the spring G rests in the notch or recess d⁴, but cannot be entirely withdrawn, and said spring D may be forced inwardly until the end d² thereof is withdrawn, so that it will not come in contact 60 with the projectile.

The oblong casing b may be formed integrally with the sleeve B or separately, and if formed separately it may be held in place by a set-screw M or in any desired manner; 65 and this device is simple in construction and perfectly adapted to accomplish the result for which it is intended, and it is evident that changes in and modifications of the construction herein described may be made without 70 departing from the spirit of my invention or sacrificing its advantages.

The spring g may be pulled out whenever desired, in order that the projectile-spreading spring D may also be disconnected from 75 the casing b.

Having fully described my invention, I claim as new and desire to secure by Letters Patent—

1. The combination with the end of the barrel of a gun, of a sleeve mounted thereon, and provided at one side with an oblong casing, the outer end of which is open and a spring which is mounted in said casing, and adapted to be adjusted therein, and the end of which projects and is curved inwardly, so as to come 80 in contact with the projectile, substantially as shown and described.

2. The combination with the end of the barrel of a gun, of a sleeve mounted thereon, and 90 provided at one side with an oblong casing, the outer end of which is open and a spring which is mounted in said casing, and adapted to be adjusted therein, and the end of which projects and is curved inwardly, so as to come 95 in contact with the projectile, a transverse spring mounted therein for retaining the first-mentioned spring in place, notches formed in the sides of the casing with which the retaining-spring engages, substantially as shown 100 and described.

3. The combination with the end of the barrel of a gun, of a sleeve mounted thereon, and provided at one side with an oblong casing,

the outer end of which is open and a spring which is mounted in said casing, and adapted to be adjusted therein, and the end of which projects and is curved inwardly, so as to come
5 in contact with the projectile, a transverse spring mounted therein for retaining the first-mentioned spring in place, notches formed in the sides of the casing with which the retaining-spring engages, and said casing being pro-
10 vided with a bottom plate which conforms in cross-section to the shape of the barrel of the gun, and the adjustable projectile-spreading

spring being mounted on said plate and adapt-
ed to slide thereon, and said plate being
slightly convex longitudinally on its outer sur-
face, substantially as shown and described. 15

In testimony that I claim the foregoing as my invention I have signed my name, in presence of the subscribing witnesses, this 17th day of March, 1896.

CHARLES J. STABERG.

Witnesses:

C. GERST,
M. A. KNOWLES.
